PUMP FOR DISPENSING CANS

Samuel H. Smith, Atlantic City, N. J., assignor to
Emma R. Dawson, Atlantic City, N. J.

Application April 29, 1947, Serial No. 744,571

1 Claim. (Cl. 222—385)

1

My invention relates to new and useful improvements in dispensing cans, and, more particularly, to the pump that is either built into the can, or fitted within a can.

Another object of the invention is to provide a dispensing can of the type mostly used for outboard motors. As is well known, the fuel tank of an outboard motor is relatively small; and after the engine has been run for an hour or two, it is necessary to refuel the tank.

If the boat and outboard motor are used on inland waterways, or even rivers and bays, if the water is rough or the tide is running swiftly, the rocking of the boat makes it rather difficult to pour the gasoline from the ordinary fuel can into the tank, even though a funnel is used.

One of the principal objects, therefore, is to provide a can for carrying gasoline, in which either a pump has been built into the can, or to use the cans that are on the market, remove the cap and install the small pump, so that it is not necessary to tilt the can to refuel the tank of the outboard motor.

Still another object of the invention is to provide a small hand pump that is placed centrally of the can and so arranged that after the pumping of the fuel into the fuel tank, the gasoline in the outlet hose will drain out of the hose into the tank; and any gasoline that is in the pipe or elbow near the inner end of the hose will flow back into the dispensing can, so that there is no possibility of any of the gasoline in the hose spilling or running into the boat.

Still another object of the invention is to produce a pump that may be instantly installed in the conventional cans now used, making it unnecessary to tilt the can to refuel the tank, and wherein any gasoline in the hose will either run into the refueling tank or back into the dispensing can.

With these and other objects in view, the invention consists in certain new and novel features of construction and combination of parts as will be hereafter more fully described and pointed out in the claim.

Referring to the drawings, showing a preferred form and a modified form,

Fig. 1 is a sectional view showing my new pump built into a dispensing can;

Fig. 2 is an enlarged, sectional view of the lower end of the pump;

Fig. 3 is a sectional view taken on line 3—3 of Fig. 2;

Fig. 4 is a sectional view similar to Fig. 2, but with the piston drawing the liquid into the pump;

Fig. 5 is a sectional view similar to Fig. 1 of the modified form showing my pump fitted into the conventional dispensing can;

Fig. 6 is an enlarged, sectional view of the low-

er end of the pump, showing the piston in a partly raised position for forcing the liquid from the pump;

Fig. 7 is a side elevation of the pump taken at right angles to Fig. 5; and

Fig. 8 is a sectional view taken on line 8—8 of Fig. 6.

Referring now more particularly to Figs. 1 to 4 inclusive, showing the pump as built into a dispensing can, there is shown the can 1 with its dome 2 and the inlet 3 with the central orifice 4 with the cap 5, while centrally of the orifice 4 is the pump 6. Extending to one side of the pump 6 may be seen the outlet pipe 7, the elbow 8 fitted in the crown 2 while from the elbow 8 extends the dispensing or outlet hose 9.

In this form of pump there is provided a large plate 10 which is soldered or welded to the inner surface of the crown 2 about the orifice 4; the plate 10 also being fitted about and soldered to the piston 11. This plate 10 is also provided with apertures 12 so that if the fluid or gasoline gets above a piston 13, by pulling up the piston rod 14 the liquid above the piston 13 will run through the openings 12 back into the dispensing can 1.

This arrangement is desirable, as otherwise it might be difficult after the can has been standing for a while to raise the piston 13.

Glancing now at Fig. 2, there may be seen the valve chamber 15 which is welded or otherwise permanently secured to one side of the cylinder 11. Also there is the main port 16 leading from the lower end of the cylinder 11 into the valve chamber 15. Built in the valve chamber 15 is the upper valve seat 17 and the lower valve seat 18 with the ports 17' in the upper valve seat 17 and the ports 18' in the lower valve seat 18. Fitted within the valve seat 17 is the valve 17a and likewise fitted within the valve seat 18 is the valve 18a. These valves 17a and 18a are similar and are weighted so that they are both normally in a closed position.

There is a small cover 19 over the bottom of the chamber 15 with its central opening 20. Extending from the top of the valve chamber 15 is the outlet pipe 7 heretofore mentioned; and it will be noticed (Fig. 1) that near the upper end of the pipe 7 just below the crown 2 there is the small orifice 21, the purpose of this being that after the piston rod 14 has been operated, any gasoline in the tube 9 will naturally flow out through the tube 9; but if the outer end were elevated or there was any gas back of the rear end of the hose 9 or in the elbow 8, it will drain in to the can through the orifice 21.

Also, to make sure that there is no gas left in the tube 9 after the operator has finished pumping, he should raise the outer end of the tube 9 above the level of the can 1 and any gas

in the tube 9 will drain back into the elbow 8 and out through the orifice 21 into the fuel tank.

Of course, when pumping the gas from the can 1, a small amount will be shot through this orifice 21 back into the can 1 but the opening is so small that the amount that goes back into the can 1, rather than being dispensed, is negligible.

Thus it will be seen in refueling an outboard motor it can be done without spilling a drop in the boat or on the deck.

The operation of the valve is easily understood, so only a brief reference is made thereto. When the piston rod 14 is raised (Fig. 4) the suction will cause the gasoline in the can 1 to pass up through the opening 20 and the suction will also raise the valve 18a off its seat 18 and cause the gasoline to pass through the port 18' through the port 16 and up into the cylinder 11. The suction and the weight in the meantime will both tend to close the upper valve 17a.

Referring now to Fig. 2, which shows the downward stroke of the piston 13, the pressure will cause the lower valve 18a to close as the port 16 is above this valve and will cause the upper valve 17a to rise to permit the gas to pass through the ports 17' up into the dispensing pipe 7 where a negligible part will be forced through the orifice 21; but the remainder will pass through the elbow 8, and, of course, out through the dispensing hose 9.

As heretofore mentioned, this is the type of pump that is to be used when the pump is permanently built into the can 1 as it is a little cheaper to manufacture than the modified form about to be described.

Referring to the modified form, as shown in Figs. 5 to 8, it will be understood that this form is to be applied to the dispensing cans now in general use.

The central orifice or opening is generally two and one-eighth inches (2 $\frac{1}{8}$ "') in diameter, so that to pass this pump within this type of can, it is necessary to use a different form of valve chamber than that shown in Fig. 2 of the preferred form, as the over-all diameter of the cylinder and the valve chamber in this form is greater than two and one-eighth inches (2 $\frac{1}{8}$ "').

Therefore, instead of building the valve chamber to one side of the cylinder, I construct it at the bottom of the cylinder, so that the pump may then easily be fitted within the opening of the standard type of dispensing can. In this instance, the pump and the dispensing pipe and tube form a unit that may readily be passed within the orifice of the can and a cap screwed over the plate about to be mentioned, and the tank then ready for use.

Referring now to Fig. 5, there is shown the cylinder 25. It will be noticed that at the top thereof there is welded or soldered a central plate 26 to rest on a flange 27 about the central opening 28 in the crown 29 of the can 30. There is also provided a top 31 of the cylinder 25 that fits over the plate 26. There is also a screw cap 32 which is cut out centrally to leave the flange 33 to clamp down on the plate 26 that, it will be remembered, is secured to the cylinder 25. Thus, when the pump is placed in the central orifice 28 and the screw cap 32 is turned down in position, it will tightly clamp the plate 26 and the pump in place. Over the usual inlet 34 is fitted a metal cap 35.

Referring now to Figs. 6 and 7, there will be

seen welded or soldered to the bottom of the cylinder 25 the cylindrical valve chamber 36. There will also be seen the port 37 in the bottom of the cylinder 25 that leads into the auxiliary chamber 38 with the port 39 leading from the auxiliary chamber 38 to the valve chamber 36. There will also be seen the lower valve seat 40 with its ports 40' and the valve 40a fitted on the valve seat 40. Likewise there will be seen the upper valve seat 41 with its ports 41' and the fitted valve 41a. Also may be seen the port 42 located above the valve 41 which leads into the dispensing pipe 43. This pipe 43 also has the small opening 44 near its upper end and just before it passes through the plate 26. The pipe is then bent as at 45 to which is attached the dispensing hose 46.

The valve chamber 36 also has a small opening 47 in its bottom for the entrance of the fluid into this chamber. There is a piston 48 with a piston rod 49 that passes up through the plate 26 and top plate 31; and there will be a small handle 50 at the top of the piston rod 49.

I can also use a packing nut 51 about the piston rod 49 and this may also be used in the preferred form.

The pumping operation and the movement of the valves are exactly the same as in the preferred form, that is, when the piston 48 is pulled upwardly, the lower valve 40a will rise off its seat 40 and the upper valve 41a will remain closed so that the cylinder 25 will fill up with gas. Here and on the down-stroke the pressure on the valve 40a will close the same and the under pressure on the upper valve 41a from beneath will open 35 the same, so that the liquid will be forced into the dispensing pipe 43 and out of the tube 46.

Also near the upper end of the cylinder 25 there are the plurality of orifices 52 so that if any liquid gets above the piston 48 the up-stroke of the piston 48 will cause it to flow out of these orifices 52 back into the can.

Thus, it will be seen that the action and arrangement in both the preferred and modified forms is practically the same, with the exception 45 that in the modified form, the pump may be used and sold as a unit and installed in cans that are now on the market, due to the fact that the over-all diameter is less than that of the central opening in the present cans.

From the foregoing, it will be seen that I have provided a pump that may be permanently built into a can; or temporarily fitted in cans now in use, so that it is not necessary to tilt the can when refuelling the tank; and it is also possible 55 to refuel an outboard motor even though the boat is rocking, without spilling a drop of gasoline on the motor, or on the boat, or in the boat.

It will be understood that throughout the specification I have mentioned the special adaptability 60 of the can for use with outboard motors. However, the can may be used as an auxiliary tank to be carried in an automobile and used in an emergency; or, in fact, it may be used wherever a small quantity of gasoline is to be dispensed.

Furthermore, the parts are readily assembled and the unit type, or the modified form may be placed in a standard can within a matter of moments.

Having thus described my invention, what I claim is new and desire to secure by Letters Patent is:

In combination with a small dispensing can having a central opening, a pump, comprising a cylinder, a plate secured at the upper end of the cylinder and provided with openings for drain-

age purposes, spaced slightly inwardly from the periphery, said plate permanently secured in the can beneath said opening, a valve chamber secured to one side and near the lower end of said cylinder, a port leading from the port to the valve chamber, an upper and lower valve in said valve chamber and spaced respectively above and below said port, an inlet port for the valve chamber and an outlet pipe from the valve chamber, a flexible hose connected to said outlet pipe, the outlet pipe passing through the upper portion of said can, a piston for drawing fluid into the cylinder and for forcing it out of the cylinder through the outlet pipe, and the outlet pipe provided with a small orifice near its upper end and 15

within the can, whereby any fluid remaining in the outlet pipe above the orifice, after pumping, will drain back into the can.
